UNITED STATES PATENT OFFICE.

FRANK B. ALLEN, OF CYNWYD, PENNSYLVANIA, ASSIGNOR, BY MESNE ASSIGNMENTS,
TO FRANK H. DUNBAR, OF CLEVELAND, OHIO.

HOPPER CONSTRUCTION.

Application filed June 20, 1924. Serial No. 721,319.

This invention relates to hopper construction, particularly ash hoppers for mechanical stokers.

One object of the invention is to provide 5 a new and improved hopper construction for collecting and discharging the ashes and siftings from a mechanical stoker.

Another object is to construct an ash siftings hopper adapted to discharge the ashes 10 collected therein into a main ash hopper located adjacent thereto.

A further object is to construct an ash siftings hopper provided with fluid means 15 for discharging ashes and siftings therefrom.

Another object is to construct a main hopper and an auxiliary hopper, normally separated from each other, but adapted to be brought into communication with each 20 other at all times regardless of the amount of material in the main hopper.

A still further object is to construct adjacent hoppers, each provided with means for discharging water thereinto and having a 25 system for collecting the water from the hoppers, including a unitary water discharge means for both hoppers.

Other objects ancillary to the foregoing will appear and be pointed out in the following specification and drawings:

In the drawings attached hereto and forming part of this specification,

Fig. 1 is a vertical section taken on line 1-1 of Fig. 2 and showing hopper construction embodying my invention.

Fig. 2 is a view taken substantially on line 2-2 of Fig. 1.

Fig. 3 is a view similar to Fig. 1 taken substantially on line 3-3 of Fig. 4 and 40 showing another form of my invention.

Fig. 4 is a side elevation taken on line 4-4 of Fig. 3 with the side wall 1 broken away and certain parts omitted to expose the hopper.

Fig. 5 is a view of a modified form of 45 my invention, similar to those shown in Figs. 1 and 3, the view being taken substantially on line 5-5 of Fig. 6.

Fig. 6 is a side elevation taken on line 50 6-6 of Fig. 5 with the side wall 1 broken away and certain parts omitted to expose the hopper.

Mechanical stokers of the present day 55 type require the customary hopper to receive the major bulk of the ashes, clinkers,

etc., discharged from the end of the stoker, and also a supplemental of siftings hopper, as it is frequently termed, the function of this supplemental or siftings hopper being to catch the fine, partially burned coal and fine 60 ashes which, falling through the stoker, are not discharged into the main hopper. Such siftings hopper are usually of substantially the same width as the stoker and may be of about the same length. Usually they 65 comprise a totally separate and distinct hopper independent from the main hopper with independent ash discharge openings. It is difficult and often inconvenient to construct these hoppers with bottom discharge 70 openings so disposed as to discharge the contents of the hoppers into an ash car which runs on tracks below the main hoppers. These cars are usually not of sufficient width to catch all of the ashes discharged from 75 those hoppers which are out of alignment with each other, as regards the center of the car track. The independent siftings hopper, having its own bottom discharge opening, also occupies a considerable amount 80 of valuable head room.

I have constructed a hopper, however, which saves much head room while preserving adequate hopper capacity and high efficiency, and which is adapted to discharge 85 its contents through the discharge opening of the main hopper. I have furthermore provided hoppers of the type involving the independent siftings hopper with new and improved means of discharging contents 90 from the siftings hopper, and a unitary means for collecting and conducting away from the siftings hopper and also the main hopper all the water which may have been discharged thereinto.

In Figs. 1 and 2, I have illustrated one 95 form of hopper construction embodying my invention in its preferred form. The concrete and steel floor beams are indicated by the numeral 1. 2 indicates, as an entirety, 100 a mechanical stoker mounted on or above the floor carried by the beams 1. 3 designates a main ash hopper and 4 indicates a siftings hopper, both hoppers being located below the stoker 2 and supported in part from the floor beams 1 of a boiler house. The main hopper 3 consists of upright side, bottom and end walls 5 and top wall 6, having an opening 7 beneath the end of stoker 2 to receive ashes discharged from the end of the 110

stoker, and one or more bottom openings 8, each provided with a door 9 to serve as a closure for the openings or to be withdrawn when the ashes in the hopper are to be discharged therefrom. These doors 9 are preferably of the shape and construction of the door shown in my U. S. Letters Patent No. 1,547,284 and may be operated by a cylinder (not shown) and connecting rods 92 disposed between and below the doors. These doors run on rollers 9^b which are carried by shafts 9^c mounted on girders 9^d, and are in part guided between guide strips 9^e which are carried at the inner ends of the shafts. 10 indicates a stationary water collecting trough suspended from the hopper at one end of each opening 8, into which trough water passing through the hopper 3 and onto the door 9 may be discharged so that substantially all water passing through the openings 8 of the hopper is conducted away through a suitable pipe 11 to a place of disposal, leaving the underside of the hopper dry at all times, regardless of the quantity 20 of water which may be sprayed into the hopper as by sprinklers 3^a to expedite the cooling of the ashes. It will be noted that the opening 7 in the top of the hopper is relatively narrow and is disposed closer to the 25 rear wall (righthand wall in Fig. 1) of hopper 3 than to the front wall thus permitting top wall 6 to extend laterally and rearwardly from the front wall. The purpose 30 of this location of opening 7 and the extension of top wall 6 from the front wall 5 will appear hereinafter.

Siftings hopper 4 is formed with substantially vertical side walls 12 and inclined bottom wall 13, which slopes from just beneath 40 the floor at the front end of stoker 2 downwardly at such an angle that it meets the front wall of hopper 3 at a point well above the bottom of hopper 3. The rear end wall of hopper 4 preferably constitutes part of 45 the front wall of hopper 3 and a portion of this wall is made up of a series of movable wall sections or metal plates 14, each secured to a shaft 15, which is rotatably mounted in floor beams 1 and provided with a handle 16 or other suitable power applying means, and 50 a counter weight 17 of suitable form to facilitate rotational movement of the shaft 15 and elevation of the plates 14 into substantially the dotted line position in Fig. 1. It 55 will be noted that the plates 14 may be moved into the dotted line position of Fig. 1 at any time, regardless of the normal accumulation of ashes in hopper 3, inasmuch as the plates are so located as always to be 60 above the angle of repose of ashes passing through opening 7. At the front of hopper 4, I have provided means for releasing fluid under pressure into the hopper to discharge the ash contents therefrom into the hopper 65 3 through opening 14^a provided, when the

plates 14 are elevated to bring the hoppers 3 and 4 into communication with each other. This means may take various forms, but in the form illustrated it consists of a water pipe 18 extending across the hopper 4 near the front end thereof, and one or more jets 19, or outlets therefrom, with the openings disposed to discharge water substantially parallel to the top surface of bottom wall 13.

In operating the construction shown in Figs. 1 and 2, the ashes discharged from the stoker 2 fall through the opening 7 into hopper 3 and accumulate therein until discharged therefrom through the bottom opening 8 by movement of the doors 9 or either of them. The fine ashes and siftings which fall through the stoker 2, or for any reason do not pass through opening 7 of hopper 3, are collected on the top of wall 6 as at 6^a and in siftings hopper 4 from which hopper they may be periodically discharged into hopper 3 by elevation of the wall plates 14 and discharging water under pressure through nozzles 19. Any water discharged into hopper 4 will naturally run into hopper 3 and be discharged from the bottom thereof into the trough 10 and pipe 11.

It will be obvious to those skilled in the art that jets 19 may be employed to cool the ashes similarly to jets 3^a in hopper 3, or other jets for this purpose may be inserted in pipe 18 as desired.

It is to be noted that no opportunity is offered for air to enter through the hoppers and pass through the fire on the stoker, since the only openings in the hoppers below the fire are openings 8, which are, however, except during the discharge of ashes therefrom, substantially water-sealed by reason of the novel construction of the doors 9 and parts associated therewith. The wall plates 14 which serve to separate the hoppers 3 and 4 from each other or permit these two hoppers to be brought into communication with each other, are not in contact with the outer air and, therefore, may be operated at any time without damage to the fire, due to air passing therethrough. It is thus possible to prevent substantially any air passing up through the fire on grate 2, even when the ashes are being discharged, since when the doors 8 are opened, the wall plates 14 may be closed and any air passing through the opening 8 will continue through the hopper 3 and opening 7 and thence into the stack.

In Figs. 3 and 4, I have illustrated a slightly modified form of hopper construction, which in contrast to that illustrated in Figs. 1 and 2 includes a separate and distinct siftings hopper provided with independent bottom discharge openings located alongside of the discharge means from the main hopper, and employing a novel means for collecting and disposing of the water passing through the two hoppers.

- 1 indicates floor beams of a boiler house, certain of these beams 1 being omitted from Fig. 4. 2 indicates a stoker similar to stoker 2 of Fig. 1. 23 indicates the main ash hopper having a sprinkling means 3^a, and 24 indicates the ash siftings hopper. 25 indicates the front and rear walls, and 25^a the side walls of hopper 23. 6 indicates the top wall through which opening 7 permits 70 ashes discharged from the rear end of stoker 2 to be discharged into hopper 23. The bottom of hopper 23 is provided with one or more bottom discharge openings 28, through which ashes may be discharged from the 75 hopper, for each of which openings there is provided a door 9 operated by rod 9^a and cylinder 9^b and similar in substantially all respects to the doors 9 of Figs. 1 and 2. One or more stationary troughs 10 (and in 80 20 this case one) are provided to receive water passing through the hopper opening 28 and collected by the doors 9, from which trough 10 and pipe 11 serve to lead the water to a place of disposal.
- 25 The siftings hopper 24 is provided with sloping side walls 32 of substantially the same pitch, a sloping front wall 33 and an upright rear wall 34 adjacent and preferably secured to wall 25 of hopper 23. Hopper 30 per 24 is provided with a bottom discharge opening 35, to which is fitted a door 36 resembling the doors 9 in substantially all respects, except perhaps size, the door being provided with actuating means, such as 35 hand wheel 37, shaft 37^a, rack 38 and pinion 39. Along one end of opening 35, I provide a stationary trough 40 adapted to receive water discharged through the opening 35 and over door 36, this trough in substantially all respects except perhaps size resembling trough 10. Attached to the lower end of trough 40 is a pipe 41, which extends through wall 25 into hopper 23 and discharges the water from the trough 40 into 45 the interior of hopper 23.
- Each hopper 23 and 24 is provided with 50 sprinkling means 3^a for spraying water onto the ash content of the hoppers to cool the same quickly. The unitary system for collecting the water discharged into these hoppers comprises doors 9 and 36, troughs 10 and 40 and pipes 11 and 41, as will appear from the drawings and the foregoing description. If it is found necessary to employ fluid under pressure to remove ashes from either or both of the hoppers, suitable means, such as the jets 19 of Fig. 1 may be employed with the construction shown in 55 Figs. 3 and 4 as desired.
- 60 It will be noted, by referring to Fig. 4, that I have shown a modified form of main hopper 23, where the side walls 25^a converge and the bottom openings are in the center of the hopper, rather than at either side, as in Fig. 2. It is to be understood, 65 however, that the form of siftings hopper shown in Fig. 4 may be employed equally well with the form of main ash hopper shown in Fig. 2, it only being necessary to locate the trough 40 so that it may discharge 70 into the interior of hopper 23.
- In Figs. 5 and 6, I have shown a slightly modified form of hopper construction and a modified form of the system for collecting 75 water from the hoppers. In Fig. 5, 1 indicates the floor beams of a boiler house, certain of these beams 1 being omitted from Fig. 4, 2 the mechanical stoker, 3 the main ash hopper and 44 the siftings hopper, each having sprinkling means 3^a. 5 indicates the 80 upright walls of the hopper 3, and 6 the top wall of this hopper. 7 indicates the opening through the top wall for the ashes discharged from the end of the stoker 2. 8 indicates the bottom discharge opening for 85 the hopper 3. 9 indicates the door or doors cooperating with the opening or openings 8. 10 indicates the stationary trough to receive water from the hopper 3, which passes through opening 8 and off door 9. 11 indicates the discharge pipe from trough 10.
- The siftings hopper 44 is provided with one substantially vertical side wall 42, an inclined side wall 43, an inclined front wall 44^a and a rear wall 45, which may be secured 90 to and form a part of the upright front wall 5 of hopper 3. The bottom of hopper 44 is provided with an opening 46 fitted with a door 36, which cooperates therewith and which is actuated by any suitable means, 95 for example, a hand wheel 37, shaft 37^a, rack 38 and pinion 39. Along one end of the opening 46, I have provided a trough 47 to receive water passing through the opening 46 and across door 36, and have connected 100 this trough 47 directly with trough 10 by means of a connection 48, so that water discharging into trough 47 will pass freely into trough 10 and thence into pipe 11. These 105 connections form a unitary system for collecting and disposing of the water discharged into the hoppers.
- Walls 43 and 44^a are inclined at such an angle that ash siftings collecting thereon 110 may not always be readily and completely discharged therefrom when the door 36 is opened. Accordingly, I provide a suitable fluid ejecting means near the upper ends of the walls 43 and 44^a. Such a means may 115 take the form of water pipes 18 having one or more jets 19 (see Fig. 1) arranged to discharge water downwardly along the top surface of the walls and substantially parallel thereto.
- It will be observed, by reference to Figs. 120 to 6 inclusive, that I have constructed a unitary system for collecting and disposing of water discharged into a plurality of hoppers. In the structure shown in Figs. 1 and 2 the water from hopper 4 flows directly into 125

hopper 3, is collected by door 9 and disposed of through trough 10 and pipe 11. In the structure shown in Figs. 3 and 4 the water in hopper 24 is collected outside of hopper 23 but discharged thereto and passes thence as in Figs. 1 and 2. In the structure shown in Figs. 5 and 6 the water of hopper 44 is collected as in hopper 24 but is led directly into trough 10 and pipe 11 of the adjacent hopper 3 without going through hopper 3.

The details and construction of the doors 9 and 36 and the troughs 10, as well as the parts cooperating with the doors, including the tracks and rollers therefor, are not specifically described nor claimed in this application, but form the subject matter of a copending application, now Patent No. 1,547,284.

Having thus described my invention, what I desire to secure by Letters Patent is defined in what is claimed.

What is claimed is:

1. In combination with a furnace having a mechanical stoker, a main hopper and an ash siftings hopper disposed in position to receive material from the stoker, the ash siftings hopper being disposed beneath the mechanical stoker and comprising side walls, a rear end wall having movable sections and a bottom wall located beneath the stoker and inclined upwardly from the said rear end wall and terminating adjacent to the front end of the stoker, the main hopper being separated from the siftings hopper by the said rear end wall and having a discharge opening in the bottom portion thereof, means disposed near the upper-end of the bottom wall of the siftings hopper to discharge fluid into the siftings hopper for moving solid substances from the siftings hopper through the rear end wall thereof and into the main hopper, and a movable closure for said discharge opening provided with means controllably to retain solid material in the hopper and to collect and discharge fluid passing through the discharge opening.

2. In combination with a furnace having a mechanical stoker, a main hopper disposed to receive material from the stoker and having a discharge opening in its lower portion and having upstanding side walls, a movable ash retaining closure for the said discharge opening, a siftings hopper disposed to receive material from the stoker and communicating with the said main hopper through one side wall thereof and above the said bottom discharge opening thereof, to discharge material into the main hopper, means to discharge liquid into each hopper and means associated with the said closure to collect and discharge liquid passing through the said bottom discharge opening.

3. In combination with a furnace having

a mechanical stoker, a main hopper having a discharge opening in the lower portion thereof and having upstanding walls, a movable ash retaining closure for the said opening, the said main hopper being disposed to receive material from the stoker, a siftings hopper disposed beneath and in material receiving position with respect to the stoker and communicating with the main hopper through one wall thereof and above the said discharge opening, the wall between the two hoppers including sections mounted to swing into the main hopper, means on the exterior of the hopper to move the said movable sections and means in the siftings hopper to discharge liquid to move solid material therein into the main hopper.

4. A hopper construction comprising a main hopper having an opening in the lower portion thereof, a solid material retaining closure for the said opening, a supplemental hopper adjacent to the main hopper and communicating therewith, means for discharging liquid into each hopper, means for discharging liquid from the supplemental hopper into the main hopper, and means including the said closure for collecting and conducting away water passing through the said opening.

5. In combination with a furnace having a mechanical stoker, a main ash hopper disposed to receive material from the stoker and having a discharge opening in the lower portion thereof, an ash retaining door for the said opening, means discharging water into the main hopper, a supplemental hopper communicating with the main hopper and disposed to receive material from the stoker, means for discharging water and solid material from the said supplemental hopper into the main hopper and means including the said door, for collecting and conducting away the combined water of both hoppers which passes through the said discharge opening.

6. In combination with a furnace having a mechanical stoker, a main hopper and a siftings hopper both disposed in position to receive material from the said stoker, the siftings hopper communicating with the main hopper above the surface of ashes normally reposing therein, a portion of the wall separating the hoppers being suspended to swing freely into the main hopper above the ashes therein, and liquid means to discharge solid material from the siftings hopper into the main hopper, the main hopper having a discharge opening in its lower portion provided with a liquid collecting, solid material retaining closure.

7. In combination with a furnace having a mechanical stoker, a main hopper disposed to receive material from the stoker and having a discharge opening in its lower portion, a liquid collecting and discharging door

for the said opening, a siftings hopper disposed to receive material from the stoker and communicating with the main hopper above the surface of the ashes normally 5
posing therein, a portion of the wall separating the said hoppers being formed in sections, each section being hung at its top to swing freely into the main hopper at all times, and liquid means to remove solid 10
material from the said siftings hopper into the main hopper.

8. Hopper construction comprising a main hopper having front, side and rear walls, a top wall provided with a solid material inlet opening remote from the front wall, and a bottom wall provided with a discharge opening and a movable solid mate- 15

rial retaining closure therefor; and adjacent, open top, solid material receiving hopper communicating with the main hopper 20 through the said front wall and well above the bottom of the main hopper, the said front wall of the main hopper having sections movable at all times to separate the said hoppers or to permit communication of 25 the hoppers with each other, liquid means in the adjacent hopper for conducting solid material therefrom into the main hopper, and means associated with the said closure to collect and conduct away the liquid passing through the said discharge opening.

In testimony whereof I hereunto affix my signature this thirteenth day of June, 1924.

FRANK B. ALLEN.
